Primary Examiner — Susan Bennett Hattan*Assistant Examiner* — Janice Hallmark(74) *Attorney, Agent, or Firm* — QuickPatents, LLC; Kevin Prince(57) **CLAIM**

I claim the ornamental design for a snuffer tool, as shown and described.

DESCRIPTION

FIG. 1 is a perspective view of a snuffer tool, showing my new design;

FIG. 2 is a front elevational view thereof, the rear elevational view, left-side elevational view, and right-side elevational view all being identical thereto;

FIG. 3 is a top plan view thereof;

FIG. 4 is a bottom plan view thereof; and,

FIG. 5 is a cross-sectional view thereof, taken along lines 5-5.
